VENEERING PRESS AND THE LIKE

Adolf Fischer-Schmutz, Basel, Switzerland

Application June 28, 1938, Serial No. 216,383
In Switzerland July 7, 1937

3 Claims. (Cl. 144—281)

Prior art veneering presses are known which include a pressure container, closed by a mat of rubber or the like on its side opposite the work-supporting table, and pressure is exerted on the work from this container by means of high pressures produced in the latter. A disadvantage of this type of press is that it requires intermittent and alternate raising and lowering of the pressure therein, upon the introduction and/or removal of a work piece from the supporting table. This procedure is undesirably time-consuming.

The purpose of the invention is to provide a more economical pressing device of the above mentioned kind, in which according to the invention a drum is used, divided by a partition into two chambers which can be charged from outside and are in closable connection with a source of air under pressure, the drum being rotatable on a horizontal axis in such a way that while in one chamber a wooden piece placed on the partition stands under the pressure of air through the agency of a mat spread over it, for the purpose of pressing plies together or for veneering, the drum can be rotated on the horizontal axis so that the other chamber can be charged with a work piece in the same manner as the first, and alternate charging of the two chambers in a continuous working operation is made possible.

An example of embodiment of the invention is shown in the accompanying drawings.

Figure 1 shows the complete apparatus.

Figure 2 is a longitudinal section of the drum divided into two chambers.

Fig. 2a is a cross-sectional detail on an enlarged scale, taken along line 2a—2a of Fig. 2.

Figure 3 is a cross section on the line III—III of Figure 2.

Figures 4 and 5 show similarly to Figures 2 and 3, a longitudinal section and a cross section of the same drum, but with somewhat differently charged chambers.

Fig. 5a is a cross-sectional detail on an enlarged scale taken along line 5a—5a of Fig. 5.

The press for pressing wooden plies together or for veneering, more particularly a curved wooden object, as shown in Figs. 1, 2 and 3, includes a press A actuated by air under pressure, comprising a horizontally arranged rotary drum a divided into two chambers a¹ and a² by a partition b. This drum a has on its exterior two guide rails a³ which rest on rollers c on a base support c so that the drum a can be rotated at will in either direction about its horizontal axis. The two chambers a¹, a² are connected by respective pipes d¹, d² with a source of air under pressure,

such as for instance a compressor n diagrammatically indicated in Figure 1 through closing members n¹, n² (stop valves) also diagrammatically indicated in Figure 1, and are in addition connected with one another by a pipe d³ provided with a stop cock d. The partition b is constructed as a double walled heating plate with cross passages in which heating resistances e are arranged. Further heating resistances e¹ are carried in longitudinal tubes f which are secured on and close to the wall of the drum a in both chambers a¹, a² opposite the partition b. Both chambers a¹, a² have doors h at one end by which they can be opened and hermetically closed.

The compressor n may be of any desired size and/or capacity. It is preferably capable of generating an air pressure of 6 atmospheres. The pipes d¹, d² which interconnect the compressor and chambers a¹, a² are of sufficient length to enable the drum a to be rotated through at least a 1/2 revolution in order to bring either chamber a¹ or a² to the uppermost position.

For gluing together of plies or for veneering curved wooden pieces by the aid of the press A, use is made of a base plate i lying on a table B, upon which plate the first wooden piece prepared for gluing together of the plies or veneering is placed. For example it can be assumed that in the first operation in the chamber a¹ a shaped wooden piece r is to be furnished with a veneer r¹ to be glued on to the curved external surface thereof. After a pliable, air tight mat o for instance of rubber has been laid in as good contact as possible on the wooden piece r, and the mat pressed at its margins against the plate i by a frame k and clamps m acting thereon, the plate is pushed into the open chamber a¹ on to the partition b with which it makes a substantially air tight fit round its margins. The chamber a¹ is then hermetically closed, the electric heating resistances e, e¹ switched on and the chamber a¹ then put under an air pressure of about 6 atmospheres through pipe d¹ by opening valve n¹, which has the result that the wooden piece lying under the mat o is put under pressure for veneering by the pressure of the gradually warming air on the mat. In the meantime the chamber a² is brought uppermost by rotating the drum a and in the same way as chamber a¹ is charged with a work piece to be pressed which is also covered with a rubber mat. The chamber a¹ is then closed air tight and the stop cock d opened so that the pressure is equalized and a pressure of about 3 atmospheres thus reigns in both chambers. In this way a saving of heated air under pressure

is effected. Now after closing the cock *d* the chamber *a*¹ is again brought uppermost by rotating the drum and the air under pressure released to enable the finished piece to be removed, while the air pressure in the chamber *a*² now in the lowermost position, is raised to 6 atmospheres by opening valve *n*² of the pipe *d*² in order to press the piece in this chamber in a similar way to that in chamber *a*¹. In this way the chamber *a*¹, *a*² can be charged alternately with workpieces in a continuous working operation, so that the described apparatus can be worked very economically.

So that air which may still be present beneath the rubber mat *o* when either of the chambers *a*¹, *a*² is charged, can escape, holes *i*¹ are provided in the plates *i* and shallow grooves *b*¹ communicating with the outside air, as shown in Fig. 2a in both faces of the wall *b*.

Instead of electrically, the chambers *a*¹, *a*² and the partition *b* could be heated by means of hot water or steam.

In addition to being charged each with one curved workpiece, the two chambers *a*¹ and *a*² can be charged with wooden panels to be veneered or to have their plies glued together, as shown in Figures 4 and 5. For this purpose, starting again with chamber *a*¹ on the carrying plate *i* for example two additional heating plates *s* and *s*¹ are provided in superposed arrangement, which are connected at their ends with one another and with the plate *i* by linkages *v*. One of the panels *u*, *u*¹ which, for example, is to be built up by gluing plies together, is inserted between the members *i* and *s* and the other between the member *s* and *s*¹. To permit this insertion of the panels *u* and *u*¹ the two heating plates *s* and *s*¹ are raised as much as necessary by a lifting device as for instance a screwing device *w* as indicated in Figures 5 and 5a. On the uppermost heating plate, a mould *t* is placed on which a curved workpiece *t*¹ consisting of a plurality of plies is to be shaped and glued up. This whole work of preparation is again carried out, as explained above, on the table *B*, and the mat *o*¹ again spread over the prepared charge after a

frame *p* has been placed around the charge to prevent the mat *o*¹ from being forced in between the plates *s*, *s*¹ and *t* by the air under pressure. Beyond this the procedure is as above described;

5 after the mat *o*¹ has been pressed around its margins by the frame *p* and the clamps *m* acting thereon, the whole charge unit is pushed into the chamber *a*¹, the chamber after closing put under heat and air pressure and the drum 10 then rotated for charging the chamber *a*² in the same way as chamber *a*¹ and so on.

What I claim is:

1. A pressing apparatus of the character described comprising a drum rotatable on a horizontal axis, a flat transverse diametrically-extending partition in said drum dividing the latter into two separate hermetically-closable chambers, heating means located in said partition, valve-controlled conduit means for independently and alternately interconnecting each of said chambers with a source of air under pressure, a valve-controlled conduit interconnecting said two chambers, work-supporting means for each said chamber adapted to be seated on the respective faces of said partition, said supporting means including a base plate, a flexible mat of air-impervious material covering the work, a frame for pressing the margins of said mat against said base plate and a clamping device for securing said base plate and frame together, and a table with the surface of which the respective faces of the partition can be brought into flush relationship by a half revolution of said drum.

35 2. A pressing apparatus as set forth in claim 1, each said chamber comprising heating means arranged adjacent the inside wall of the drum.

3. A pressing apparatus as set forth in claim 1, said supporting means also comprising a plurality of heating plates in superposed arrangement on said base plate and a frame adapted to be placed around these superposed heating plates to prevent air pressure from forcing said mat between said heating plates.

ADOLF FISCHER-SCHMUTZ.
